(57) **CLAIM**

The ornamental design for the lighted switch, as shown and described.

DESCRIPTION

The lighted switch can be widely used in car equipment, household electrical products, front doors, garages, lockers, and so on, especially suitable for keys and switches on devices or machines used in the outside or in the darkness. FIG. 1 is a perspective view of a lighted switch in accordance with the present design, as viewed from above; FIG. 2 is a perspective view thereof as viewed from below; FIG. 3 is a front elevational view thereof (a rear elevational view would be identical to FIG. 3);

FIG. 4 is a top plan view thereof;

FIG. 5 is a bottom plan view thereof;

FIG. 6 is a right side elevational view thereof (a left side elevational view would be identical to FIG. 6);

FIG. 7 is a sectional elevational view taken along line 7—7 in FIG. 4; and,

FIG. 8 is a sectional elevational view taken along line 8—8 in FIG. 3.
